UNITED STATES PATENT OFFICE.

HOWARD O. STEPHENS, OF PITTSFIELD, MASSACHUSETTS, ASSIGNOR TO GENERAL ELECTRIC COMPANY, A CORPORATION OF NEW YORK.

WATER-COOLED TRANSFORMER.

1,394,044.

Specification of Letters Patent.

Patented Oct. 18, 1921.

Application filed March 25, 1919. Serial No. 285,043.

To all whom it may concern:

Be it known that I, HOWARD O. STEPHENS, a citizen of the United States, residing at Pittsfield, in the county of Berkshire, State of Massachusetts, have invented certain new and useful Improvements in Water-Cooled Transformers, of which the following is a specification.

My invention relates to stationary induction apparatus, such as transformers and the like and has for its object the provision for an improved construction therefor which is rugged, cheap and economical.

More specifically my invention relates to 15 transformers and the like which utilize a minimum of material and yet must deliver large currents so that it is convenient and desirable to mount them on the machine served by such electrical apparatus. My invention 20 is thus particularly adapted to meet the requirements for transformers used on welding machines.

In machines consuming large currents, such as welding machines where the current 25 often has a magnitude in the neighborhood of 50,000 amperes, the losses in the leads alone preclude the use of transformers situated at a distance from the machine. The transformers must therefore be light and occupy as little space as possible especially 30 when the machine itself is portable.

In meeting these requirements in space and materials the problem of cooling becomes one of some difficulty of solution; 35 since the permissible space occupied excludes cooling by a circulating medium such as oil. The clearances between turns also become so small that cooling by the circulation of air is impractical, and the core itself 40 prevents cooling by radiation from being effectual over a large proportion of the windings.

In carrying my invention into effect I have, however, by a novel arrangement of 45 parts provided adequate cooling utilizing both the principles of convection and of conduction without materially increasing the space originally occupied by the windings themselves. This I have accomplished by 50 forming the electrical conductors, particularly those in the low voltage winding, in a manner adapted to convey a fluid cooling medium (water for instance) along an edge

thereof whereby the heat in the other parts of the conductor is rapidly conveyed away. 55

For a more complete understanding of the nature and objects of my invention reference should be had to the following detailed description taken in connection with the accompanying drawing in which:

Figure 1 is a perspective view of a transformer constructed in accordance with my invention. Fig. 2 is a section taken on a vertical plane perpendicular to the plane of the laminations. Fig. 3 is a horizontal section taken in the plane of the windings; while Fig. 4 is a perspective view of one of the secondary coils.

Referring now to the drawings, 10 denotes a laminated core of magnetic material having 70 three legs 11, 12 and 13, as clearly shown in Fig. 3.

The central leg 12 has an insulating covering 14 and is surrounded by the windings.

The high voltage winding, which in welding service is connected as the primary, comprises a coiled conducting tube 15; each layer being shown as having six turns. The leads for this winding comprise the tubular connections shown at 16 and 17 to which the 80 cooling circulating medium, preferably water, is admitted from some non-conducting tubing such as rubber hose (not shown). The layers of this high voltage winding 15, which are shown for the transformer illustrated in Fig. 2 as six in number, are spaced apart sufficiently to have a layer of the low voltage or secondary winding 20 inserted therebetween. A secondary layer is also placed above and below the end layers of 90 the winding 15, thereby making in all seven secondary layers for the transformer illustrated.

These secondary layers 20, as shown in Fig. 4, comprise one turn each and may with 95 advantage be made out of two similar U-shaped strips of conducting material brazed or welded together save at the outer edge where it is beaded or rolled to receive a tube of conducting material. This tube, 100 shown at 21, is also U-shaped, and is sweat-ed, brazed or welded to the edge of the one turn secondary 20 in a manner providing good thermal conductivity between the conductor and tube.

The tubes 21 for the seven conductors 20

are connected so that the circulating fluid, such as water, will pass successively through each; the extended terminal tubes shown at 22 and 23 being adapted to serve as inlets and outlets for this circulating fluid. The connections between the successive portions of tube 21 around each layer of the turns 20 are made through short U-bends 24 which are bent back against the face of the laminations as shown in Figs. 1 and 2 in order to get a better distribution in space of the parts.

The edges of conductors 20 which contain tubes 21 are formed so as to project over and beyond the tubular primary winding 15, which is interleaved between conductors 20. In this way the vertical space occupied by the two windings is a minimum, since by this arrangement the tubes 21 are not superposed upon the tubular windings 15, but occupy a space of their own to one side of the primary.

The primary and secondary are preferably bare although a coating of insulating material such as enamel will doubtless at times be expedient. To insulate the primary and secondary apart, I employ an insulating covering such as sheet asbestos for this duty which is made to envelop the secondary and is formed out of sheet insulating material in the following manner: A strip is cut from a sheet of stock and folded once in the form of a U-member 25. This insulating U-member is slipped over the secondary from the inner edge so that it is not unduly distended at its fold by the tube 21.

This U-member 25 is cut along the fold for a little distance as shown at 26 in Fig. 3 in order to provide a portion projecting over the yoke portion of secondary turn, denoted 20' in Fig. 4.

Between the two projecting slotted portions 26 of the U-members 25 is a narrow strip of the yoke 20' which would yet be exposed but for a small insulating U-member 27 that is made from a piece of the sheet stock, which is slipped over the conductor 20 at this point, preferably again from the inside edge.

The secondary conductors 20 are connected in parallel as shown for delivering large current. For this purpose the end portions 28 are bent down so as to be united together to form the terminals 29.

The core is shown as held together by the usual core clamps 30 which may be provided with suitable brackets 31 for mounting the apparatus.

The windows in the core are made only slightly wider to accommodate the tube 21 than they would be were no such tube employed. By reason of the tube 21 being on the outside edge rather than on the inside edge, a shorter mean turn of conductor is used than would have been the case were

the alternate construction used; which construction results in reduced copper losses.

It is also seen that the primary and secondary are assembled snugly together in a manner, without spacing, which permits 70 sufficient cooling in spite of the large currents employed.

It is also apparent that the cooling of conductors 20 along one edge, creates along this edge a zone of relatively low temperature 75 compared with the rest of the conductor when traversed by current, to which zone the heat in the other parts of the conductor flows due to the fairly steep temperature gradient which is in this manner created 80 across the conductor.

In operation the circulating fluid is fed to the pipe connections of the primary and secondary through non-conducting tubing leading the fluid from any convenient head of 85 pressure. This fluid is generally made to flow continuously therethrough, although this is preferable, it is not necessary.

Having now described what is at present the best means known to me for carrying out 90 an embodiment of my invention, I would have it understood that such means are merely illustrative and that I do not mean to be limited thereby to the exact details shown nor in the choice of recognized equivalents except as defined in my claims hereunto appended.

What I claim as new and desire to secure by Letters Patent of the United States, is:—

1. In an electric apparatus, the combination with a core, of a winding supported thereon, and means for circulating a cooling medium through a portion of said winding to cool it by convection, the remaining portion being cooled by conduction. 100

2. In an electric apparatus, the combination with a core, of a winding supported thereon comprising means for circulating a cooling medium through a portion of each of certain predetermined turns, the balance 110 of each of said turns being arranged to conduct heat to said portion.

3. In an electric apparatus, the combination with a core, of a winding supported thereon comprising a single turn per layer, 115 each turn having a tubular formation traversing a portion thereof, and means for circulating a cooling medium through said formation to cool such portion of said turns by convection, the remaining portion being 120 cooled by conduction.

4. In an electric apparatus, the combination with a core, of a winding supported thereon comprising single turns per layer, each turn having an edge provided with a 125 tubular formation connected with the formations on adjacent turns, and means for circulating a cooling medium in said formations.

5. In a transformer, the combination with a core, of interleaved layers of high and 130

low voltage windings, and means secured along the edges of the low voltage winding whereby the edges of said low voltage winding are cooled by convection.

5 6. In a transformer or the like, the combination with a core, of interleaved layers of high and low voltage windings, and tubular means for conveying a cooling fluid about and in contact with edges of said low voltage 10 layers.

7. In a transformer or the like, the combination with a core, of interleaved layers of high and low voltage windings, and piping connections for a cooling fluid formed about

the edges of said low voltage layers and arranged in thermally conducting relation therewith.

8. In a transformer or the like, the combination with a core, of interleaved layers of high and low voltage windings, and a pipe 20 adapted to convey a cooling fluid secured in thermal conductivity with one edge of each low voltage layer, the pipes of all the layers being connected to convey the cooling fluid in succession therethrough. 25

In witness whereof, I have hereunto set my hand this 19th day of March, 1919.

HOWARD O. STEPHENS.
